UNITED STATES PATENT OFFICE.

RAYMOND EARL WARD AND CHARLES CROWL, OF EAST PALESTINE, OHIO.

VALVE.

1,104,944.

Specification of Letters Patent. Patented July 28, 1914.

Application filed January 30, 1913. Serial No. 745,077.

To all whom it may concern:

Be it known that we, RAYMOND EARL WARD and CHARLES CROWL, both being citizens of the United States, and both residing 5 in East Palestine, Columbiana county, State of Ohio, have invented a certain new and useful Valve, of which the following is a specification.

This invention relates to valves for use in 10 connection with pumps and other apparatus of all kinds, where liquids and semi-liquids are acted upon.

The invention has particular application 15 to pumps for water, clay, and the like, and is so described in this specification, although it is not so limited.

The objects of the invention are: First: to simplify the valve, render it rugged and strong in construction, and composed of few 20 parts. Second: to accommodate irregularities in setting up the valves and their operating mechanism. Third: to combine two valves with a pump or similar apparatus, so that the pressures will be balanced, and to 25 operate the said valves by positive, although simple, mechanism. Fourth: to provide an automatic device for taking up wear. Fifth: to take the place of puppet valves in pumps and the like, and overcome the objections of 30 such valves. These and further objects will more fully appear from the following specification and accompanying drawings, considered together or separately.

In the drawings: Figure 1 is a plan view 35 of two valves, embodying the invention, used in connection with a pump. Fig. 2 is a side elevation of the same. Fig. 3 is a longitudinal section of an inlet valve embodying the invention, shown in Figs. 1 and 2, on an enlarged scale. Fig. 4 is a cross-section of the 40 same, taken on the line 4—4 of Fig. 3. Fig. 5 is a similar view, but with the parts in a different position. Fig. 6 is a sectional view of the valve shown in Fig. 3, but at right angles thereto, and Fig. 7 is a longitudinal section of an outlet valve.

In all of the views, like parts are designated by similar reference characters.

Referring to the drawings, it will be seen 50 that the new valve is shown in connection with a pump.

In Figs. 1 and 2, the complete apparatus 55 comprises the inlet valve *a*, outlet valve *b*, pump cylinder *c*, and steam cylinder *d*, the latter being connected to the piston rod *e*, and reciprocating the latter. The inlet pipe

f is connected to the inlet valve *a*, and the outlet pipe *g* to the outlet valve *b*. The inlet valve *a* is connected to the pump cylinder *c* by means of a pipe *h*, while the cylinder *c* is connected to the outlet valve *b* by a pipe *i*. The liquid is drawn into the pump cylinder through the pipes *f*, valve *a* and pipe *h*, and expelled through the pipe *i*, valve *b* and pipe *g*. To permit this to be done, each valve has 60 a barrel or moving member with a port, which is brought into coincidence with a port in its body at the proper moment, the inlet valve being open during the suction stroke, while the outlet valve is open during 65 the expelling stroke of the pump. The details of each valve are as follows, each valve being substantially alike: The inlet valve 70 will first be described. The valve comprises a body 1, preferably cylindrical in shape, 75 open at each end, and having flanges as shown, for the attachment of the heads. The body is shown as supported by means of a foot 2. At one end of the body is the head 3. This head is connected to the inlet 80 pipe *f*, or *i*, as depends upon whether it is the inlet or outlet valve. To the other end of the body is attached the head 4. The head 4 of the inlet valve, and the head 3 of the outlet valve is each provided with a 85 gland or stuffing box 5. Within the body is the drum or barrel 6, making a close fit with the interior of the body. The barrel has a port 7, extending through it. We prefer to make the barrel hollow as shown, to reduce 90 weight and cost. This port 7 communicates with a port 8 in the head 3, which communicates with the inlet pipe *f*, or *i*, as depends upon whether the valve is the inlet or outlet valve. The drum 6 is given a partial rotary 95 movement, for the purpose of bringing the ports 7 and 8 into and out of coincidence by means of a shaft 9. This shaft passes through the stuffing box 5 in the head 3 or 4, and is connected to the drums 6—6. 100 Where two valves are used, as shown, they are connected one to each end of the shaft. To make a connection which will be self-aligning, and will be cheap and durable, each end of the shaft is provided with a cross-head 10, which rests in a groove or notch in the barrel or drum 6. This notch is longer than the cross-head, and is also deeper, so that it may have some movement, so that the shaft need not be in exact alignment with the 110 center of the body or barrel, nor is it necessary that the two valves be exactly spaced

in relation to one another. The barrel partakes of a swivel motion, and hence permits itself to adjust itself to the surface of the contacting head. Each barrel is shorter than the inside length of the body, so that a chamber 11 is left at one end of the barrel. In this chamber is a diaphragm 12, which makes a close fit with the inside of the body and engages with the end of the barrel. 10 This diaphragm is caused to engage with the barrel by means of the spring 13. In the inlet valve, the shaft 9 passes through the center of the diaphragm, so that it may rotate without rotating the latter. The diaphragm has a port 14, in line with the port 8. The principal object of the diaphragm is to maintain a perfect face upon each end of the barrel. To prevent rotary movement of the diaphragm, which would disalign the 15 ports 8 and 14, a key 15 is provided, which slides in slots in the inside of the body, and in an extension 16 on the diaphragm. The chamber 11 is connected to the pipe *h* or *g*, by means of a port 17. All of the joints 20 within the body are preferably ground joints, to prevent leakage.

For the purpose of rotating the shaft so that the valves are operated properly, the following mechanism is employed: The 25 shaft 9 carries a lever 18, which is connected to a bell crank 19. A rod 20, sliding in bearings so that it is parallel to the piston rod *e* is connected to the bell crank, so that, upon its being alternately reciprocated, it will swing the bell crank upon its pivot, and thus alternately rotate the shaft 9 in one or the other direction for a period of a revolution sufficient to entirely open and close each 30 valve. The rod 20 is screw-threaded, as shown, for attachment of nuts 21 and 22, which form adjustable abutments for the arm 23 to alternately engage against, such arm being carried by the piston rod *e*. This 35 structure permits adjustment so that the barrels may be completely reversed upon the first and last half inch (approximately) of piston stroke. In order to afford an emergency release to the mechanism should any solid object become lodged between the ports 40 of either contacting flange, and that of the oscillating barrel, while the barrel is in the act of revolving to close, we provide a rigid

spring 24 inserted in the rod 20 to allow for this.

The operation of the complete apparatus 45 is apparent from the foregoing description.

The discharge in each valve is through the chamber 11, thus equalizing the pressure upon the entire diaphragm. The valves may be used singly and in other situations 50 than that described.

The valve has a large field of utility, as it may be employed with hot and cold water, steam, oil, clay and other liquids and semi-liquids. The valve is particularly applicable 55 to the clay industry, taking the place of the spring and clapper valve, which has proven very inefficient, our valve permitting a rapid cut-off.

In accordance with the provisions of the 60 patent statutes, we have described the principle of our invention, together with the apparatus which we now consider to represent the best embodiment thereof; but we desire to have it understood that the apparatus 65 shown is merely illustrative and that the invention may be carried out in other ways.

Having now described our invention, what 70 we claim as new and desire to secure by Letters Patent, is:—

1. The combination with two valves, and 75 a pump cylinder, each valve having a body, a barrel therein, a port within the barrel, a single shaft connecting the two barrels, and connections between the cylinder and the 80 valves for opening and closing the latter.

2. The combination with a valve body, a barrel therein occupying less than the entire 85 length of the body and having a passage therethrough, there being an outlet port 90 from and an inlet port to the body, a pivoted device within the body, and between the barrel and the inlet port, said device being held against rotary movement, and means for 95 yieldingly engaging the device with the body.

This specification signed and witnessed 90 this 23d day of January, 1913.

RAYMOND EARL WARD.
CHARLES CROWL.
